UNITED STATES PATENT OFFICE

166,515

PACKING SHEET FOR FRAGILE ARTICLES

Philip M. Williams, Oakland, Maine

Application March 14, 1951, Serial No. 14,477

Term of patent 14 years

(Cl. D58—13)

To all whom it may concern:

Be it known that I, Philip M. Williams, a citizen of the United States, residing at Oakland, State of Maine, have invented a new, original, and ornamental Design for Packing Sheet for Fragile Articles, of which the following is a specification, reference being had to the accompanying drawing, forming part thereof.

Fig. 1 is a top plan view of a packing sheet for fragile articles, showing my new design;

Fig. 2 is an edge view thereof;

Fig. 3 is a bottom plan view thereof; and

Fig. 4 is a side edge view thereof.

I claim:

The ornamental design for a packing sheet for fragile articles, as shown.

PHILIP M. WILLIAMS.
